HENRY J. HEDLER, OF OCCUM, CONNECTICUT, ASSIGNOR TO FRANK B. RICKETSON, OF TAFTVILLE, CONNECTICUT.

FILLING-EXHAUSTION-DETECTOR MECHANISM FOR LOOMS.

1,237,903.

Specification of Letters Patent.

Patented Aug. 21, 1917.

Application filed January 8, 1916. Serial No. 70,032.

To all whom it may concern:

Be it known that I, HENRY J. HEDLER, a citizen of the United States, residing at Occum, in the county of New London and State 5 of Connecticut, have invented a new and Improved Filling-Exhaustion-Detector Mechanism for Looms, of which the following is a specification, reference being had to the accompanying drawings, forming part 10 thereof.

This invention has reference to improvements in mechanism for detecting the exhaustion of filling in the shuttle of a loom provided with mechanism to replenish automatically the filling in the running shuttle directly or through substitution of a shuttle having a supply of filling for the running shuttle in which the supply of filling has reached the predetermined point of exhaustion. 20

One object of my present invention is to so construct filling exhaustion detecting devices adapted to operate in conjunction with means for actuating filling replenishing mechanism that wear of the feeler lock and the actuator for the transmitter is avoided under the normal operation of the feeler. 25

Another object of the invention is to provide an improved feeler and feeler controlled lock for filling exhaustion detecting mechanisms whereby the exhaustion of the filling from the running shuttle may proceed to a greater degree than heretofore in order to avoid undue waste of filling. 30

Other objects of the invention will appear from the following description.

The invention consists in the novel means normally to move the feeler lock out of its locking position under operation of a loom 40 and with a predetermined supply of filling in the running shuttle.

The invention also consists in such other novel features of construction and combination of parts as shall hereinafter be more 45 fully described and pointed out in the claim.

Figure 1, represents an end view of portions of a loom for the purpose of illustrating approximately the application thereto of the improved filling exhaustion detecting mechanism. 50

Fig. 2, represents a top plan view of portions of the breast beam and the lay of a loom with the improved filling exhaustion detecting mechanism applied thereto and 55 shown in relation to the transmitter mecha-

nism of ordinary construction through the operation of which filling replenishing or shuttle changing mechanism may be brought into action in any manner known in this art.

Fig. 3, represents a view of portions of the breast beam and parts of the transmitter mechanism, with the transmitter slide and one of the transmitter levers shown in section as on line 3-3 Fig. 2.

Fig. 4, represents a sectional view of parts 60 of the same as taken on line 4-4 Fig. 2.

Fig. 5, represents a similar view as taken on line 5-5 Fig. 2, and

Fig. 6, represents a sectional view of parts 70 as taken on line 6-6 Fig. 2 to illustrate the operation of the feeler lock by the feeler under normal conditions of the filling in the running shuttle when the lay, with the shuttle, moves toward the breast beam.

Similar characters of reference designate 75 corresponding parts throughout.

As shown herein in its preferred form the improved feeler lock is adapted, when the filling in the running shuttle is reduced or exhausted to a predetermined point or diameter, to constitute a connection between a positively operated actuator and transmitter mechanism of any known kind which transmitter mechanism in itself constitutes no part of the present invention. In the 85 present instance as more specifically referred to herein such transmitter mechanism is of a well known nature adapted, when brought into operation, to effect the actuation of a filling replenishing mechanism whereby the 90 ejection of the removable filling carrier A from the shuttle B, when exhausted to the predetermined point and the substitution therefor of a carrier having a supply of filling is accomplished. 95

Shuttle B is of a known construction to permit of such change of filling carriers A and has the usual slot in its wall to permit the approach of the detector or feeler to the filling on said carrier. As is usual in looms 100 of this general nature the shuttle B is carried by the lay C which is provided with a shuttle box D and is moved toward and from the breast beam E in the beating up operation.

Mounted on the breast beam E or to some member appertaining to such beam is the guide 7 preferably positioned at a point on said beam opposite the position of the shuttle box D. In this guide 7 is slidable the 110

transmitter slide or movable element 8 having the upwardly curved arms 9, 9, which extend beyond the inner edge of breast beam E, and also having, in the upper main portion 5 of said slide, the transverse groove or channel 10. In this groove 10 is engaged the free end of the lever 11 which latter is pivotally mounted on the breast beam E and has the slot 12 adapted to operate along 10 the cam or bent fingers 13, 13 of the usual transmitter lever 14 which is pivotally mounted on the breast beam E and is engaged with the slot 15 of the well known 15 transmitter arm 16 mounted on the shaft 17 whereby through the operation of the transmitter slide 8 in one direction motion is transmitted to the filling replenishing mechanism as heretofore.

Pivots sustained between the arms 9, 9 20 of the transmitter slide or movable element 8 is the feeler lock 18 having the depending blade 19 and the locking tooth 20 of a suitable shape to be engaged at times by a coöperating actuator operating in a direction 25 to effect, through such engagement, the movement of the transmitter slide or element 8 in its motion transmitting direction. The actuator preferably used for this purpose comprises the member 21 having at its 30 upper portion the bent end 22 adapted, at times, to engage the tooth 20 of the feeler lock 18, and its lower end is pivotally mounted on the fulcrum f of the lever 23 said actuator having the extension 24 which is 35 mounted on said lever 23 for adjustment to increase or decrease the swing of member 21.

Operation of lever 23 is effected by cam 25 mounted on the usual cam shaft F and adapted to effect the lifting of the free end 40 of said lever 23 coincidently with the movement of the lay C toward the breast beam E, and preferably during the latter part of such movement. The relation of this movement of this actuator member 21 and the lay 45 C will however depend somewhat upon the nature of the work to be accomplished by the transmitter mechanism and also to the particular means for effecting movement of the feeler lock 18 to swing its tooth 20 out of the 50 path of the actuator member.

The feeler used in this improved apparatus is such that it is interposed between and, at times, is to some extent, independent of the actuator engaging means or locking 55 member 18 and of the filling in the loom shuttle. At the same time the feeler of preferred construction is always in position to sustain the locking member 18 by the contact of the blade 19 with the feeler. To this 60 end I provide the breast beam E or some appurtenance thereof with the frame 26 having the stop lip 27 and in this frame 26 I pivot the arm 28 overbalanced to swing toward the stop lip 27 and having at its upper 65 end the feeler blade 30 having the head

31. To further assist in swinging this arm 28 toward the stop lip 27 I may employ the spring 29. With this construction it will be seen that by the bearing of the blade 19 of locking member 18 against the feeler head 70 31 the downward swinging of the toothed or free end of member 18 is limited by the feeler and that a slight movement of the feeler toward the breast beam E results in the swinging upward of such free end of 75 member 18 to carry its tooth 20 out of the way of the actuator.

The feeler blade 30 is of a nature to be received through any usual opening or slot in the shuttle box and the corresponding 80 opening in the wall of the shuttle B whereby said feeler blade 30 may at times feel against the filling in the shuttle. That is, in the movement of the lay C toward the breast beam E, the shuttle being then momentarily 85 in shuttle box D, the filling in the shuttle may strike the feeler blade 30 and the movement of such feeler blade as a result of contact with such filling will depend to a large degree upon the amount or diameter of the 90 filling then in the shuttle. Such degree of movement of the feeler being of course transmitted by its head 31 to the blade 19 of locking member 18 to effect suitable swinging movement of said member. 95

In the beating up movement of the lay the lever 23 follows the periphery of cam 25 to the small diameter of said cam to permit the actuator member 21 to swing in a retractive or non-active direction relative to the tooth 20 of lock member 18 and said member 18 is limited in its movement to follow end 22 of said actuator member 21 by the coöperation of its blade 19 with the feeler so that while the lock member 18, at this time, is in position to have its tooth 20 engaged by the end 22 of actuator 21 on the forward or working stroke of said actuator no wearing riding action occurs between the parts 18, 20 and 22, with suitable 100 adjustment of the actuator 21 relative to the lever 23 and the cam 25 the end 22 of the actuator 21 will not necessarily move backward, in its non-active direction, beyond the point at which it may engage with the tooth 20 of lock member 18. That is to say that during the greater portion of the beating up and return movement of the lay these parts 18, 20 and 22 will be in engagement but will be at rest. 105

Under normal conditions of the filling in the shuttle, on the movement of the lay toward the breast beam and before the cam 25 actuates lever 23, the feeler 30 will meet the filling in the shuttle and by such filling will be moved toward the breast beam, in such movement head 31 of the feeler will act against the blade 19 of lock member 18 and will effect the swinging of lock member 18 upward sufficiently to carry its tooth 20 out 110 115 120 125 130

of the path of the end 22 of actuator 21. This actuator will thus be operated by cam 25 through lever 23 but without effecting operation of the transmitter slide or element 8.

Owing to the fact that the actuator is normally in engagement with the transmitting mechanism, by means of lock member 18 and its tooth 20, and that but a slight movement of blade 19 is necessary to move member 18 out of such position of engagement it is practicable to so adjust this device that almost the entire filling in the shuttle may become exhausted before the transmitting mechanism is brought into action to operate the filling replenishing means.

Blade 19 of lock member 18 is by its leverage in effect a motion transmitting and multiplying device whereby a comparatively slight action on said blade 19 by the feeler 30 through its head 31 is transmitted in increased degree to lock member 18. It being evident that, with blade 19 of a suitable length a very slight movement thereof will be sufficient to effect the swinging of lock member 18 to carry its tooth 20 out of the position of engagement or out of the path of the actuator end 22.

On the other hand a very slight degree of exhaustion of filling beyond the point at which the member 18 is moved out of position of engagement of its tooth 20 will result in such reduced movement or projection of the feeler 30 by the filling that its

head 31 will not actuate blade 19 of lock member 18 sufficiently to swing tooth 20 out of engagement with the end or member 22 of actuator 21 and hence the movement of said actuator 21 through lever 23 40 and cam 25 will cause the movement of lock member 18 and the transmitter slide 8 to which said lock member 18 is connected, to be shifted in its guide whereupon lever 11 is operated and the operation of said lever 45 is transmitted to any well known mechanism for effecting the replenishing of filling in the running shuttle or the substitution for the shuttle from which the filling has been used to the predetermined point. 50

While I have herein disclosed a specific construction of my improvement I do not intend thereby to limit my invention except as herein claimed.

Having thus described my invention I 55 claim as new and desire to secure by Letters Patent—

A detector mechanism of the nature described, comprising a transmitter means having a slide, a locking hook pivotally mounted on a member of said slide and having a depending blade, a pivoted actuator arm having an upper hook engaging end normally in non-riding sustaining relation to said hook, a feeler arm pivotally mounted and having a feeler blade adapted to be controlled by contact with filling in a shuttle and in turn to control said locking hook by direct contact with its blade. 65

HENRY J. HEDLER.
